UNITED STATES PATENT OFFICE.

WILLIAM E. HARRIS, OF NEW YORK, N. Y.

ORE-FURNACE.

SPECIFICATION forming part of Letters Patent No. 248,740, dated October 25, 1881.

Application filed February 12, 1881. (No model.)

To all whom it may concern:

Be it known that I, WILLIAM E. HARRIS, a citizen of the United States, residing at New York, in the county and State of New York, have invented new and useful Improvements 5 in Furnaces for Roasting Ores, of which the following is a specification.

This invention relates to furnaces for roasting auriferous and argentiferous ores; and it 10 consists in the combination, with a fire-chamber and a roasting-chamber divided from each other by a horizontal partition, which is provided with a series of holes for communication between the chambers, of a series of hollow 15 formers open at one end and adapted to be connected with the holes of the partition at such end in an upright position. It also consists in making the hollow formers to taper toward the open end thereof.

20 This invention is illustrated in the accompanying drawings, in which Figure 1 shows the furnace partly in end view and partly in cross-section. Fig. 2 is a vertical longitudinal section. Fig. 3 is a detailed perspective view 25 of one of the formers.

Similar letters indicate corresponding parts.

The letter A designates the fire-chamber; B, the roasting-chamber; C, the horizontal partition dividing the chambers from each other, 30 and D the formers.

The roasting-chamber A is open at the top for the admission of ore, the same being provided with covers E at that place, and it has also a discharge-opening at one end provided 35 with a door, F.

The fire-chamber B is provided with a grate, G, below which is situated the ash-pit B', and both the fire-chamber and the ash-pit are provided with a door, H or H', the door of the 40 ash-pit being so arranged that when it is closed the air is shut off from the ash-pit. From the upper and rear part of the fire-chamber B extends a chimney, I, while from a similar part of the roasting-chamber extends a flue, K, into 45 the chimney, this flue being provided with a damper, L.

In the horizontal partition C are formed 50 holes J, through which the chambers A B may communicate with each other, and with which the formers D are adapted to be connected in an upright position by being fitted into them

at one end, as shown. The formers D are hollow and are open at the end designed to be connected with the holes J, which constitutes the lower end thereof, the same being more- 55 over made to taper toward such end.

In the upper portion of the fire-chamber B are arranged air-flues o, which are respectively provided with a cap, p, at the outer end, for closing them.

60 Into the lower portion of the fire-chamber B projects a steam-pipe, Q, which is open at the inner end and provided with a valve, r, at a suitable point outside of the furnace.

In applying the apparatus to use the formers 65 D are put into place and ore is introduced into the roasting-chamber A in the form of a pulp, a suitable quantity of salt being mixed therewith to render it capable of caking. A fire is now started on the grate G, the damper L in 70

the roasting-chamber being closed, and the products of combustion passing directly into the chimney I from the fire-chamber. When the fire is fairly under way the door H' of the ash-pit is closed to prevent the entrance of air 75

thereto, and then the valve r of the steam-pipe is opened, so as to admit steam to the ash-pit beneath the grate, which, being decomposed, increases the heat of the fire to a material extent. The amount of steam thus admitted, however, 80

must be so gaged that the fuel is barely moistened, if at all, to avoid putting out the fire. The pulp which is thrown into the roasting-chamber A packs closely around the formers D, as indicated in Fig. 2, and the heat from 85 the fire-chamber B passes into the formers at their lower open ends, thus acting on the ore, an opening being also preferably left at the upper end of the formers, so that the heat may pass directly through them. When the pulp 90

has been heated a sufficient length of time to form a skin or shell around the formers D, and thus to support itself in the roasting-chamber—say about one-half hour—the formers are withdrawn, and in this manner flues D' are 95

left in the ore, through which the heat then circulates to complete the roasting operation, the body of the pulp being kept out of direct contact with the fire. The withdrawal of the formers D is obviously facilitated by their peculiar shape, and to further facilitate this act 100 the sides of the formers are lubricated with oil

or other suitable material before they are placed in position. The damper L in the roasting-chamber is opened when the fire ceases to smoke, so that while this chamber is kept free 5 of smoke the spent heat is permitted to pass therefrom directly into the chimney. After the ore has been brought into the sulphate condition it is drawn from the furnace and bathed or washed in hot water until all the base-metal 10 sulphates are thoroughly removed, the same being soluble in hot water. The precious metal is then left in a free condition, ready for amalgamation.

I am aware that a furnace for roasting ore 15 has been constructed with a fire-chamber and an ore-chamber connected by air-flues, a horizontal supplemental floor being arranged in the ore-chamber and provided with a series of holes in which are adapted to be placed the lower 20 ends of a series of solid rods of a length greater than the depth of the ore-chamber, which are sustained at their upper ends by iron guides, all in such manner that, the solid rods being in position, and the ore-chamber charged, and the 25 ore leveled down, the rods can be removed, thereby leaving a number of small flues through the body of ore, after which the fire is started and the products of combustion pass through the flues in the ore. A furnace constructed in 30 this manner and having this mode of operation is not my invention, and is not claimed by me. In my structure I employ hollow formers having their lower open ends adapted to be connected with or disconnected from the openings 35 through the horizontal partition which divides the fire-chamber and roasting-chamber, whereby the heated air from the fire-chamber can

pass directly into the formers, thereby heating the ore adjacent to the formers and forming a skin or shell around the latter, so that when 40 they are removed the flues through the ore will be sustained and retained in their form by such skin or shell.

What I claim as new, and desire to secure by Letters Patent, is—

1. In a furnace for roasting ores, the combination, with a fire-chamber and a roasting-chamber divided by a horizontal partition having a series of openings through the same, of a series of hollow formers open at their lower 45 ends and adapted to be connected with or disconnected from the openings through the horizontal partition, substantially as described, whereby the heat from the fire-chamber passes into the formers through the lower open ends, 50 as and for the purposes set forth.

2. In a furnace for roasting ores, the combination, with a fire-chamber and a roasting-chamber divided by a horizontal partition having a series of openings through it, of a series 55 of removable and replaceable hollow formers open at their lower ends and tapering on their exterior toward said lower open ends, substantially as described, said formers being adapted to be connected with or disconnected from the 60 openings through the horizontal partition, as and for the purposes set forth.

In testimony whereof I have hereunto set my hand and seal in the presence of two subscribing witnesses.

WILLIAM E. HARRIS. [L. S.]
